UNITED STATES PATENT OFFICE.

THOMAS STRAHAN, OF CHELSEA, MASSACHUSETTS.

PROCESS OF COLORING OR DECORATING PAPER FOR WALL-COVERINGS.

SPECIFICATION forming part of Letters Patent No. 430,707, dated June 24, 1890.

Application filed May 27, 1889. Serial No. 312,312. (No model.)

To all whom it may concern:

Be it known that I, THOMAS STRAHAN, a citizen of the United States, residing at Chelsea, in the county of Suffolk and State of Massachusetts, have invented an Improvement in the Process of Coloring or Decorating Paper and other Fabrics for Wall-Coverings and for other Purposes, of which the following is a full, clear, and exact description, reference 5 being had to the accompanying drawings, making part of this specification, in which—

Figure 1 is a plan of a portion of a machine for coloring or decorating paper and other fabrics in accordance with my improved process. Fig. 2 is a longitudinal vertical section of the same. Fig. 3 is an end elevation of the machine.

My invention relates to a novel method of coloring or decorating paper and other fabrics for covering walls and for other purposes, whereby beautiful and artistic effects are produced in a simple and inexpensive manner.

To this end my invention consists in projecting or discharging liquid or liquid colors in the form of spray or vapor by means of any suitable atomizing device against the surface of the paper or fabric to be decorated or colored, the paper or fabric to be treated 25 being either white or colored, wet with water or a coating of color, or dry, and the liquid ejected being either a liquid color or a liquid which will change by its chemical action the previous color of the paper or fabric or its 30 coating, or alter the same by simple dilution, different effects being produced by so manipulating the atomizer or atomizers employed as to vary the quantity or direction of the discharge, or by partially or wholly interrupting 35 the flow of the liquid from one or more of said atomizers, as hereinafter more particularly set forth.

In carrying my invention into effect I provide an atomizing device consisting of any 40 suitable number of atomizers *a* (one or more) of any well-known construction, connected by means of flexible pipes *g* with a suitable receptacle or receptacles *b*, containing the liquid or liquids or liquid color or colors to 45 be employed, said atomizer or atomizers being operated in a well-known manner by

steam or air, as preferred, which is introduced into the pipe *c*, to which the atomizers are attached, by means of a pipe *d* connected therewith and leading to the source of supply. The paper or fabric *A*, in rolls or sheets, is then carried or moved along, by means of any suitable mechanism or otherwise, in front of the downwardly-inclined nozzle or nozzles of the atomizing device at a suitable distance 55 therefrom, receiving in its passage the liquid or liquid color discharged in the form of spray or vapor from the said atomizing device, the said discharge of spray or vapor being made continuous or variable according to the effect 60 to be produced. This movement of the paper is preferably accomplished by means of an apron *B* and roller *D*, the apron *B* being that of an ordinary wall-paper-coating machine, which may be employed to coat the paper 65 with color or wet the same before it reaches the atomizing device.

The paper or fabric being treated may be either wet with water or other liquid, or dry, and may be either white or colored or coated 75 with color, and the liquid discharged from the atomizer or atomizers may be either a liquid color or it may be a liquid which will change by its chemical action or by dilution of the color of the coating the previous color 80 of the paper or fabric or its coating.

If a uniformly-rainbowed effect is desired, the jets of the nozzles of the atomizers *a* are made to play constantly on the paper or fabric as it passes in front of the same, the nozzles being so directed and the colors so selected for the different jets as to give a continuous rainbowed effect. If, however, a clouded effect is to be produced, it may be obtained by varying or interrupting the flow of 85 the color or liquid onto the paper from the receptacle or receptacles in which it is contained, which may be accomplished in any 90 suitable manner—for instance, by means of stop-cocks *f* in the supply-pipes of the atomizers *a*, or by raising or lowering, by means of any suitable mechanism, the supply-tanks *b*, into which the colors or liquids flow through pipes *h* from the closed receptacles *i* above, which raising or lowering of the 95 tanks *b* will increase or diminish the pressure on the liquid supplied to the atomizing 100 tanks *b*.

device, thus increasing or diminishing its flow.

Another method of producing a clouded effect which I have found to answer well is by interrupting the jets by periodically interposing between the same and the paper or fabric A a suitable intercepting device, which will catch the color or liquid and prevent it from reaching the paper or fabric at that particular point. This is accomplished by the employment of a series of targets or interceptors *k*, which are mounted on a frame *l*, adapted to slide transversely in suitable bearings *m*, said frame being actuated by a cord *n*, connected with a lever *p*, which is moved by a cam *r*, Figs. 1 and 3, against the resistance of a weight *s*, passing over a pulley and connected by means of a cord 10 to the opposite end of the sliding frame *l*. These targets are placed on the frame *l* at a short distance apart, as seen in Fig. 3, so as to leave spaces between the same through which the jets from the nozzles of the atomizers *a* reach the surface of the paper or fabric A, and thus, as the targets or interceptors *k* are reciprocated by the action of the cam and weight above described, the jets will be periodically interrupted, the spray which impinges on the inner sides of the targets *k* running down the surface of the same into a shallow pan or receptacle *G* beneath, from which it may be drawn off through a suitable discharge pipe or orifice, and in this manner the spray from each nozzle is alternately intercepted and allowed to play onto the surface of the paper or fabric, the targets being arranged in any suitable manner to intercept one or more of the jets at one time, and permit the remaining jets to play onto the paper or fabric through the spaces between the said targets. A similar clouded effect can also be produced by a continuous movement of the atomizers *a* during the passage of the paper or fabric in front of the same, which movement can be produced by continuously reciprocating the pipe *c*, to which the atomizers are attached. To accomplish this movement of the pipe *c*, the pipe *d* is provided with a swinging joint 15 below the apron *B* of the machine, and is connected above said joint 15 by means of a rod 17 with an eccentric 16, which imparts the desired reciprocating motion to the pipe *c* and atomizers *a* connected therewith.

An imitation of granite can be produced by causing the atomizers to throw a spray so coarse as to produce, instead of a smooth color, a spattered effect, which, by a proper selection of colors, can be made to closely imitate the various kinds of granite and other stone.

If desired, pulp in the process of being manufactured into paper or other fabric, or a wall or other surface, may be colored or ornamented in the same manner as the paper or fabric above described without departing from the spirit of my invention, as my improved process can be employed to advantage in embellishing any surface or substance to which it may be applicable, the atomizers being so arranged as to direct the spray or vapor onto the surface to be ornamented in such manner as to produce the desired effects.

An infinite variety of novel, beautiful, and striking effects, imitations of marble, stone, &c., can thus be easily and cheaply produced by the employment of atomizers as above described, it being merely necessary to vary the colors and manipulate the atomizers or periodically interrupt one or more of the jets of the same, as taste or fancy may dictate.

When used for wall-coverings, the decoration produced by my improved process as above described may, if desired, form the ground or surface, on which the design is afterward printed in the same manner as on ordinary grounded wall-paper.

What I claim as my invention, and desire to secure by Letters Patent, is—

The herein-described process of coloring and decorating paper and other fabric, which consists in projecting or discharging liquid or liquid colors in the form of spray or vapor against the surface of the paper or fabric to be treated by means of atomizers, and varying or changing the effect so produced by alternately interrupting one or more of the jets of spray at any desired point or points, substantially as set forth.

Witness my hand this 24th day of May, 100 A. D. 1889.

THOMAS STRAHAN.

In presence of—

P. E. TESCHEMACHER,
HARRY W. AIKEN.
